UNITED STATES PATENT OFFICE.

HARRY J. LEBHERZ, OF FREDERICK, MARYLAND, ASSIGNOR, BY MESNE ASSIGNMENTS, TO THE OX FIBRE BRUSH COMPANY, A CORPORATION OF WEST VIRGINIA.

BRUSH-MACHINE.

No. 920,588.

Specification of Letters Patent.

Patented May 4, 1909.

Application filed July 12, 1907. Serial No. 383,386.

To all whom it may concern:

Be it known that I, HARRY J. LEBHERZ, a citizen of the United States, residing at Frederick, in the county of Frederick and State of Maryland, have invented certain new and useful Improvements in Brush-Machines, of which the following is a specification.

This invention is particularly, though not exclusively, designed for use in connection with the brush-making machine set out in Letters Patent of the United States Nos. 578,907 and 664,989, dated March 16, 1897 and January 1, 1901, respectively, to which reference may be had; my object, primarily, being to provide a simple and efficient construction and organization of mechanism whereby, among other advantages, fibers of variable color, or possessing other different or contrasting characteristics, shall be periodically selected from a source of supply and applied in the form of tufts to the brush block, as will be hereinafter described and claimed.

In the drawings—Figure 1 is a side elevation of a brush machine embodying my invention in its preferred form, only so much of the machine being shown as is necessary to illustrate the improvements. Fig. 2 is a similar elevation, as viewed from the opposite side of the machine. Fig. 3 is an elevation, partly in section, showing the plural magazine, the fiber-separating and carrying slide, the tuft-inserting slide, and adjuncts, the parts being shown in the respective positions which they occupy immediately after the wisp of fiber has been carried to the inserting position. Fig. 3^a is a transverse section through the pivoted tuft guide, as on the line 3^a—3^a of Fig. 3. Fig. 3^b is a perspective view of said guide. Fig. 4 is a horizontal section on a plane slightly above the fiber-separating and carrying slide. Fig. 5 is a partial side elevation of the fiber separating and carrying slide, and adjuncts. Fig. 6 is a vertical section, as on the line 6—6 of Fig. 5. Fig. 7 is a partial elevation of the fiber separating and carrying slide, showing its relatively-movable member as in position to close the mouth of the fiber-gathering and holding opening. Fig. 8 is a detail of the movable stop for actuating said member. Fig. 9 is a sectional detail, showing in open position, the devices, and their connections, for holding and compressing the wisp of fiber.

preparatory to the action of the tuft-inserting slide thereon. Fig. 10 is a similar detail, showing the parts in closed position.

1 designates the supporting frame, and 2 the drive shaft of the machine. 60

3 is the table on which the blocks to form the brush-backs are supported and by which they are fed to the boring and tuft inserting devices.

4 is the boring tool for the blocks; 5 is the fiber magazine; 6 is the horizontally-reciprocating slide, by means of which quantities of fiber are successively separated from the mass in the magazine, and fed into position for insertion as tufts into the blocks, and 7 is 70 the vertically-reciprocating slide which acts to seat the fiber successively in the bored block.

8 is a horizontal shaft which is driven from the drive shaft by means of a belt 9 passing around pulleys 10, 11 on the respective shafts. The shaft 8 bears a crank arm 12 which is connected through a rock-lever 13 and links 14 with the slide 7 to effect the vertical action of the latter; and this shaft also bears a 75 cam 12' which is connected by means of a lever 16 and link 17 with the drill to effect its vertical operation.

18 is a lower horizontal shaft which is driven step by step through suitable devices 85 actuated from the upper shaft 8. The devices herein illustrated comprise an eccentric 19 on shaft 8, and an eccentric rod 20 connecting the same with a rock-arm 21 bearing a pawl 22 that engages a ratchet 90 wheel 23 on the shaft 18. This shaft 18 carries the cams 24 which, through suitable connections, effect the requisite transverse, vertical and longitudinal movements of the work-holding table 3 in order to position the brush blocks with respect to the boring and tuft-inserting devices.

25 is a horizontal shaft which is driven from the main shaft by a belt 26 passing around pulleys 27, 28, on the respective 100 shafts, and which shaft 25 is belted with a pulley on the spindle of the boring tool.

The several parts above indicated are, excepting as hereinafter particularly described, substantially similar in construction and operation with the corresponding parts set out in the Letters Patent aforesaid.

Referring to the magazine, it is to be noted that in pursuance of my present invention, it is divided into two separate compartments, 110

a, b, by means of a central vertical partition 29. These compartments are designed to contain fiber of two different kinds or colors, that, for example, in one compartment being 5 black and that in the other being white.

The fiber separating and carrying slide 6 is arranged beneath the magazine as usual, but it is so constructed and organized as to operate upon the fibrous contents of the respective compartments at predetermined intervals, in order to select fiber from one or the other compartment as the particular requirements of the brush under construction may demand. This slide in its preferred 10 form includes a long blade or bar 30 composed of two sections joined endwise by a laterally-disposed connecting piece, the opposing ends of the sections being spaced apart and formed to provide a vertical notch 31 having an overhanging lip 32 which is designed, as the slide is moved forward beneath the magazine, to engage a quantity of the overlying fibers and to force it down into the notch. On the outer side of this bar, in advance of the notch, is slidably mounted a 15 plate 33 which is provided with a forwardly-extending lip 34 adapted to close over and confine the fiber within the notch when the plate is moved relatively to the bar. This 20 plate is secured to one side of a block 35 which is slidably fitted to a longitudinal slot in the bar, and a piece 36 is secured to the opposite side of the block to prevent lateral displacement of the parts. (See Fig. 6.) This 25 piece is provided with an angular projection 37 which is adapted to co-act at prescribed intervals with certain stops to effect the longitudinal movement of the plate 33 relative to the bar, as will hereinafter appear.

Through the bar 30 is formed an opening 30 to permit the downward passage of the tuft and its inserting devices. Pivoted to one end of the bar is a link 38 which is connected through a spring-controlled frame 39 with a 45 lever 40 in engagement with a cam 12' on the shaft 8, whereby the slide is longitudinally reciprocated to move its notch or fiber-receiving portion beneath the magazine and the tuft-inserting devices alternately. The 50 frame 39 is slidably mounted on the link 38 and is held normally in retracted position thereon by means of a suitably-disposed spring 40', whereby the slide may be moved independently of the cam against the pressure of the spring. (See Fig. 3.)

The plate 33 is automatically actuated during the reciprocations of the slide to open or close the mouth of the fiber-receiving notch at predetermined intervals in a manner to permit the notch to receive and deliver the fibers from either compartment of the magazine, as desired. The rear end of the plate is engaged by the free end of a spring-arm 41 which is affixed to the bar 30, 60 the contacting parts of the plate and arm be-

ing so formed that the plate is temporarily locked in either position—open or closed—to which it may be set, as indicated in Figs. 3 and 7.

During the operation of the slide upon the 70 contents of the compartment *b*, it is necessary to interrupt the supply of fiber from the compartment *a*, to the slide. A good means for this purpose comprises a channeled piece 42 that embraces the top of the feed bar and its plate, and is adapted to be moved beneath and from the bottom of the first compartment *a* at predetermined intervals. The piece 42 is carried by an arm 43 extending from one end of a shaft 44 which is slidably 75 supported in arms 45 on the machine frame. Extending from the shaft 44 is an arm 46 which is connected by means of a link 47 with the longer arm of a bell crank lever 48, the shorter arm of which bears upon a peripheral cam 49 on the driven shaft 18. The lever 48 is held normally in engagement with the cam by the action of a spring 50 which is secured to the link 47 and to the main frame. (See Fig. 2.)

The contour of the cam is such that at prescribed intervals the lever is raised and lowered to effect the periodical reciprocations of the slide shaft 44 and thus move the cut-off device beneath and from the first compartment *a* of the magazine.

When the lever is riding upon the lower surfaces of the cam the cut-off device is in retracted position so as to permit the fiber in the first compartment (*a*) of the magazine to 100 rest upon the top of the slide bar, and hence when the notched portion of the latter passes beneath such compartment it separates a quantity of the fiber from the overlying mass. It is necessary that in this stroke of 105 the slide the mouth of the notch should be closed immediately after it has received the fiber, and for that purpose there is provided in the path of the projection 37 a stop or abutment 51 therefor. The motion of the 110 plate is arrested by the action of the stop against the projection, while the motion of the bar continues, and in consequence the parts are caused to assume their closed position, as indicated in Fig. 7. The spring 115 latch 41 engages the outer end of the plate and locks it in closed position. By virtue of the spring-frame connection between the link 38 and lever 40, relative movement of these parts is permitted when the plate has 120 been caused to assume the closing position by the action of the stop 51. The quantity of fiber thus separated and held by the slide is carried to position beneath the tuft forming and inserting devices. As the notch approaches this position, the projection 37 abuts against a fixed stop 37^x (Figs. 4 and 5) which effects rearward movement of the plate relatively to the bar, and thus uncovers the notch and unclamps the confined fiber.

110

115

120

125

130

So long as the lever 48 is held in its down position in the depressions of the cam 49, the slide continues to select and withdraw the fiber from the first compartment (a) of the magazine, but when the said lever is raised by an elevation of the cam, the cut-off device 42 passes under such compartment and temporarily checks the delivery of its contents to the slide. At that juncture the stop 51 is moved from the path of the projection 37 so as to permit the notch 31 of the bar 30 to be and remain open for the reception of the fiber from the second magazine (b). The stop 51 is conveniently formed on 10 the arm of a lever 52 which is pivoted to a bracket 53 on the main frame adjacent the magazine, and is held normally in active position by a suitably-disposed spring 54 seated in a socket in the bracket. The lever 52 is 15 provided with a shoulder 55 which lies in the path of an arm 56 on the slide-shaft 44, whereby when the latter is shifted endwise to move the cut-off device beneath the magazine, the arm impinges against the said shoulder and thereby raises the stop above the path of the slide projection. (See Figs. 4, 5 and 8.) On the bracket 53 in the path of such projection is a fixed stop 57, which is so arranged that when the notched portion of 20 the slide has passed under the second compartment and received fiber therefrom, the projection abuts against such fixed stop and is thereby caused, by the movement of the plate relative to the bar, to close the notch 25 and confine the fiber therein. In the reverse stroke of the slide, such fiber is carried thereby to position for insertion in the brush block. So long as the lever 48 is maintained in elevated position by the cam, the slide 30 continues to select and withdraw the fiber from the second compartment of the magazine. Thus, it will be seen that by varying the peripheral contour of the cam, the fibers may be selected from the respective magazines in any prescribed order so as to produce on the fibrous face of the brushes, various patterns or designs.

The vertically-acting tuft-inserting slide 7 hereinbefore referred to, and particularly described in Patent No. 578,907 aforesaid, affords a guide for the staple and staple-inserting devices whereby the tuft is fastened in the brush block. This slide in its descent straddles the wisp of fiber in the notch of the underlying carrying bar 30 in a manner to form a guide and support for the wisp as it is being carried down into the block.

As a simple and efficient means to compress and hold the body of the wisp in order that it shall be readily embraced by the two members of the slide 7, I provide the following construction:—58 is a fixed member against which the inner projecting portion of the wisp contacts when it is moved to position below the tuft-inserting slide. This

member is conveniently formed on a bracket 59 which is affixed to the main frame and it is located sufficiently beyond the fiber separating and carrying slide to leave an intervening space for the descent and guidance of the tuft inserter. In front of the fixed member is a movable member 60 which is adapted to be swung down yieldingly against the wisp so as to press and hold it in place. This movable member preferably comprises an 70 arm carried by a rock shaft 61 having its bearings in the bracket 59 and also in a bracket 62 at the opposite side of the machine. On the end of the shaft 61 adjacent the bracket 62 is an arm 63 which is connected by means of a link 64 with an arm 65 carried by a lower rock-shaft 66. This latter shaft is mounted in brackets 67 depending from the main frame. To the arm 65 is pivotally connected the lower end of a vertical rod 68, which is held yieldingly depressed by means of a spring 69 secured thereto and to the main frame. (See Fig. 2.) Thus the movable member is held down in yielding contact with the wisp of fiber by 80 the pressure of the spring. The upper end of the rod 68 has a pin and slot connection 85 with the forward arm of the rock-lever 13 previously described, whereby when such arm is elevated during the ascent of the tuft-inserting slide the rod 68 is raised therewith in a manner to swing upward the movable fiber holding member 60. The pin and slot connection affords sufficient lost motion between the rod and lever arm to insure the 90 timely operation of the connected parts.

The member 71 for aiding in forming and guiding the tuft to the brush holder is a longitudinally channeled arm carried by and movable with the rock shaft 66. Thus said 105 member 71 is swung down toward the block to the position shown by dotted lines in Fig. 3, concurrently with the downward movement of the member 60, and raised concurrently with the upward movement of said 110 member 60 to the position shown by full lines in Fig. 3.

When the member 71 is moved to the position shown by dotted lines, the channel therein is directly over the hole in the brush block and in line with the slide 7 to receive the slide and the tuft carried thereby and guide the tuft to the hole in the underlying block. When the slide 7 is raised from the channel of the member 71 and the member 115 71 is raised to the position shown by full lines in Fig. 3, said member will escape the previously driven tuft and occupy a position above the same to permit the advance of the brush block.

The lower forward end of the guide member 71 is provided with a toe or projection 72 which, when the guide is swung downward for the next succeeding tuft-inserting operation, pushes forward the adjacent seated 120 130

tufts and forms a free passageway through the channel of the member 71 for the descending tuft.

An arm 73 on one end of the shaft 66 abuts 5 against a suitably-disposed stop 74 on the adjacent bracket 67 to limit the downward movement of the arm 65 and its connections.

I claim—

1. In a brush machine, the combination of 10 a source of fiber supply; a second source of fiber supply, a tuft inserter, mechanism for taking a quantity of fiber from each source and delivering it to the inserter, and means for periodically checking the feed to said 15 mechanism of the fiber from a source of supply.

2. In a brush machine, the combination of 20 a plural source of fiber supply, a fiber-separating and carrying device movable to and from the same, and means for periodically checking the feed to said device of the fiber from a source of supply whereby said device is caused to gather a quantity of fiber from either source of supply at predetermined 25 intervals.

3. In a brush machine, the combination of 30 a plural source of fiber supply, a fiber separating and carrying device movable to and from the same, a cut-off for one source of supply, and means for actuating said cut-off at predetermined intervals.

4. In a brush machine, the combination of 35 a plural source of fiber supply, a fiber separating and carrying slide movable to and from the same, said slide comprising a bar having a fiber receiving portion and having also a relatively movable member to close said portion, a cut-off for one source of supply, means for periodically actuating said 40 cut-off, and means for actuating said member to close the said fiber receiving portion of the bar at predetermined intervals with respect to the operation of the cut-off.

5. In a brush machine, the combination of 45 a source of fiber supply, a fiber separating and carrying slide movable to and from the same, said slide comprising a bar having a fiber receiving portion and having also a member relatively movable thereon to close 50 and open such portion at intervals, and oppositely-disposed stops or abutments to effect the movement of said member relative to the bar.

6. In a brush machine, the combination of 55 a plural source of fiber supply, a fiber separating and carrying slide movable to and from the same, said slide comprising a bar having a fiber receiving portion and also a member relatively movable thereon to close 60 and open such portion at predetermined intervals, means for periodically checking the feed to said slide of the fiber from a source of supply, oppositely-disposed stops or abutments to effect the movement of said member 65 relative to the bar, an additional closing

stop for said member, and means for moving the last-named stop into and out of action at predetermined intervals.

7. In a brush machine, the combination of 70 a plural source of fiber supply, a fiber separating and carrying slide movable to and from the same, said slide comprising a bar having a fiber receiving portion and also a member relatively movable thereon to open and close such portion at predetermined intervals, means for periodically checking the feed to said slide of the fiber from a source of supply, oppositely-disposed stops or abutments to effect the movement of said member relative to the bar, an additional closing stop for said member, means for moving the last-named stop into and out of action at predetermined intervals, and yielding devices for reciprocating said slide.

8. In a brush machine, the combination of 80 a plural source of fiber supply, a fiber separating and carrying slide movable to and from the same, said slide comprising a bar having a fiber receiving portion and having also a member relatively movable thereon to open and close such portion at intervals, oppositely-disposed stops or abutments to effect the movement of said member relative to the bar, an additional closing stop for said member, a cut-off device for one source of fiber supply, 90 and means whereby the last-named stop is periodically moved out of action and the cut-off device into action, and the converse.

9. In a brush machine, the combination of 95 a source of fiber supply, a fiber separating and carrying slide movable to and from the same, said slide comprising a bar having a fiber receiving portion and having also a member relatively movable thereon to close and open such portion at intervals, means to effect 100 the movement of said member relative to the bar, and a spring latch device to lock the said member temporarily in either position to which it may be moved..

10. In a brush machine, the combination of 110 of a magazine having a plurality of fiber containing compartments, a fiber separating and carrying device movable beneath and from the said compartments, means for periodically checking the feed to said device of the fiber from one of said compartments and a tuft inserter to which the fiber is delivered by said device.

11. In a brush machine, the combination of 120 of a magazine having a plurality of fiber-containing compartments, a fiber separating and carrying device movable beneath and from the said compartments, and means for periodically checking the feed of the fiber from one of said compartments to the said device.

12. In a brush machine, the combination of 125 a fiber separating and carrying device, clamping members between which the fiber carried by said device is held and guided at the tuft-inserting point, means whereby one

of said members is held yieldingly in clumping position, means whereby said member is periodically opened, and means for engaging the fiber thus held and inserting it in the brush block.

13. In a brush machine, the combination with the tuft-inserting device, and means for operating it, of a tuft guide or casing mounted to swing in a vertical plane toward and from the brush block, and means for oscillating said guide or casing.

14. In a brush machine, the combination with the fiber separating and carrying device, of clamping members between which the fiber carried by said device is held and guided, one of said members being movable relative to the other, a tuft-inserting device, means for operating it, a tuft guide or casing mounted to swing toward and from the

brush block, and means whereby the movable member and tuft guide or casing are simultaneously actuated.

15. In a brush machine, the combination with the tuft-inserting device, and means for operating it, of a tuft guide or casing mounted to swing in a vertical plane toward and from the brush block, said guide or casing being provided at its lower forward end with a toe or projection, and means for actuating said guide or casing.

In testimony whereof, I have signed my name to this specification in the presence of two subscribing witnesses, this 6th day of July 1907.

HARRY J. LEBHERZ.
